CLAIM

The ornamental design for a finger ring as shown and described.

DESCRIPTION

1. Finger ring

1.1 : Front

1.2 : Right

1.3 : Left

1.4 : Top

1.5 : Bottom

1.6 : Perspective

1.7 : Perspective

1.8 : Back

The design consists of a finger ring with three parallel rings of cubes linked by two rows of cubes; some of the cubes in the parallel rings contain diamonds set; all the angles on the sides of the faces of the cubes are cut at 45 degrees.
